CLAIM

We claim the ornamental design for a portion control measuring device, as shown.

DESCRIPTION

FIG. 1 is an isometric view of a portion control measuring device.

FIG. 2 is a top plan view of the portion control measuring device of FIG. 1.

FIG. 3 is a bottom plan view of the portion control measuring device of FIG. 1.

FIG. 4 is a left side elevation view of the portion control measuring device of FIG. 1 of which the right side elevation view is a mirror image.

FIG. 5 is a rear elevation view of the portion control measuring device of FIG. 1; and,

FIG. 6 is a front elevation view of the portion control measuring device of FIG. 1.

1 Claim, 5 Drawing Sheets
